APPARATUS FOR BURNING FUEL

Arthur J. Boynton, Winnetka, Ill., assignor to
 H. A. Brassert & Company, Chicago, Ill., a corporation of Illinois

Application December 29, 1933, Serial No. 704,390

4 Claims. (Cl. 158—109)

This invention relates to a new and improved fuel burning device, and more particularly to a burner construction for burning of gaseous fuels.

The invention relates to a burner for use with metal treating furnaces such as reheating furnaces or with other types of furnaces where high temperatures are required. The burner construction is so designed as to provide a separate entrance for the gas and air and to provide a stratification of gas and air at the discharge from the burner.

It is an object of the present invention to provide a new and improved burner for gaseous fuel.

It is an additional object to provide a construction of this character in which the gas and air for combustion are introduced in separate strata.

It is also an object to provide a construction in which separate chambers or sections of heat resistant material may be provided for the air and gas, these sections being removably placed in the burner housing.

It is a further object to provide a burner assembly having means for determining the velocity of the gas and air issuing from the burner so that the velocity may be varied at will or maintained constant in spite of variations in the rate of flow of air and gas.

It is an additional object to provide a construction in which a lower air strata of non-oxidizing gas may be provided adjacent oxidizable substances which require to be heated, while at the same time providing combustion for heating this material.

Other and further objects will appear as the description proceeds.

I have shown certain preferred embodiments of my invention in the accompanying drawing, in which—

Figure 1 shows one form of my improved burner connected to a reheating furnace, the figure being in vertical section;

Figure 2 is an enlarged longitudinal section of one form of burner construction;

Figure 3 is a view similar to Figure 2, but showing the modified form of construction;

Figure 4 is a perspective view showing a pair of the interior chambers of the burners; and

Figure 5 is a section taken on line 5—5 of Figure 2, and shown upon a reduced scale.

Referring first to Figure 1, a reheating furnace has been shown having the hearth 11, the regenerator 12, and the air jacket or housing 13 surrounding the hearth. The air intake 14 is supplied with air by a blower 15 driven by a

motor 16, the flow of air being controlled by damper 17. The air is led from the preheating chamber through passage 18 to the burner 19. The gaseous fuel is led through passage 20 controlled by damper 21 to the burner 19.

The burner 19 is provided with a pair of gates 22 and 23, as shown in Figure 2, which are moved vertically by rods 24 and 25. The movement of these rods is controlled by the piston in cylinder 26 shown in Figure 1. Fluid under pressure is supplied to opposite ends of cylinder 26 through lines 27 and 28. This fluid under pressure is discharged through nozzle 29, the fluid being supplied through pipe 30. The nozzle 29 is pivotally supported at 31 and is restrained against movement to the left by spring 32 controlled by the adjacent wheel 33. The opposite side of the nozzle 29 is engaged by the thrust rod 34 connected to diaphragm 35 located between the chambers 36 and 37. The chamber 37 is open to the atmosphere, while the chamber 36 is connected by pipe 38 to an orifice in the burner located at 39.

The burner 19 consists in an outer housing 40 which may be made of metal and which has an upwardly extending outer opening 41 and a downwardly extending opening 42. The housing 40 of the character shown is of a size to retain two interior chambers 43 and 44, shown in perspective in Figure 4. The section of Figure 2 is taken through the chamber 44, which has an upwardly facing opening 45 in registration with the opening 41 of the housing. The chamber 43 is identical with chamber 44, but is placed in the reverse position so that its opening registers with the opening 42 in the housing.

As shown in Figure 2, the inside wall of the chambers may be inclined so as to reduce the area somewhat towards the discharge end which is controlled by the gates 22 and 23. These gates are provided with beveled edges 46 and 47, it being noted that the bevel has a longer edge in the direction from which the flow proceeds. This has the important function of reducing turbulence at this point.

The burner housing 50 of Figure 3 is similar in general design to that just described. It has been shown without any interior removable chambers, the housing itself having walls forming the chambers. This type of burner may be used where the temperature of the gases is not such as to require removable and replaceable liners of heat resistant or refractory material. In this construction the control gates 51 and 52 are carried on pivot shafts 53 and 54. These

shafts are shown as having coacting arcuate racks 55 and 56 indicated in broken lines. The operating rod 57 serves to rotate the shaft 54 and through the interacting racks the two gates are 5 simultaneously opened or closed. It will be understood that the forms of gate shown in Figures 2 and 3 may be used interchangeably with the two forms of burner housings.

While the burner has been shown as being 10 made up of two sections, it is obvious that any desired number of sections may be incorporated in the burner. It is also possible to locate the burner so that the interior chambers are superposed rather than adjacent with a vertical wall 15 between. In the use of such a burner, for example, a stratum of air may be sent below the roof to protect the roof against the excessive heat of the combustion below. The number of sections and their dimensions may be varied in 20 accordance with the particular use and the fuel employed. The length of flame will increase as the sections are widened and their number decreased for an equal total area of burner. Further, the flame with any given construction of 25 burner will be influenced by the character of the fuel used. By varying the details of the sectional construction, any desired character of flame with respect to length and maximum temperature may be obtained. With horizontal layers 30 of air and gas the lower layer of gas will prevent contact between an oxidizable member, such as metal requiring to be heated, and excess air of combustion, at the same time that the excess air will protect the roof.

35 It will be noted that the gate construction of Figure 2 is such that not only may the effective discharge area of the burner be modified, but also the axis of the flame may be raised and lowered by simultaneously moving the two gates 40 in the same direction. In this way the flame may be projected at the height and in the direction desired. By the use of an automatic control, such as shown in Figure 1, the gates may be automatically operated to maintain constant flame 45 conditions. In the simple type of control shown,

variation in the pressure in the burner acts through the medium of the control apparatus to open or close the gates.

While I have shown certain preferred forms of construction, these are understood to be illustrative only, as I contemplate such changes and modifications as come within the spirit and scope of the appended claims.

I claim:

1. A gas burner comprising a housing, similar 10 hollow sections of heat resisting material in said housing in reversed arrangement whereby air and gas may be introduced into the burner from different directions through adjacent sections of the heat resisting material.

2. A gas burner comprising a housing, similar 15 hollow sections of heat resisting material in said housing in reversed arrangement whereby air and gas may be introduced into the burner from different directions through adjacent sections of 20 the heat resisting material, the discharge openings of the sections being adjacently located and adapted to discharge parallel streams.

3. A gas burner comprising a housing, similar 25 hollow sections of heat resisting material in said housing in reversed arrangement whereby air and gas may be introduced into the burner from different directions through adjacent sections of the heat resisting material, and means for varying the effective area of the discharge from the 30 sections.

4. A gas burner comprising a housing, similar 35 hollow sections of heat resisting material in said housing in reversed arrangement whereby air and gas may be introduced into the burner from different directions through adjacent sections of the heat resisting material, the discharge openings of the sections being adjacently located and adapted to discharge parallel streams, and gates placed on either side of the combined sections for 40 varying the effective area of the discharge from the sections, said gates being independently movable whereby the effective axis of the discharge port may be moved.

ARTHUR J. BOYNTON. 45
